SIDNEY G. DOWN, OF CHICAGO, ILLINOIS, ASSIGNOR TO THE WESTINGHOUSE AIR BRAKE COMPANY, OF PITTSBURGH, PENNSYLVANIA, A CORPORATION OF PENNSYLVANIA.

SAFETY DEVICE FOR BRAKES.

1,083,351.

Specification of Letters Patent.

Patented Jan. 6, 1914.

Application filed March 18, 1910. Serial No. 550,161.

To all whom it may concern:

Be it known that I, SIDNEY G. DOWN, a citizen of the United States, residing at Chicago, in the county of Cook and State of Illinois, have invented new and useful Improvements in Safety Devices for Brakes, of which the following is a specification.

This invention relates to automatic fluid pressure brakes, and the principal object of the invention is to provide means enabling the engineer to control the brakes in case it is found that the brakes can not be operated in the usual way by manipulation of the engineer's brake valve to vary the train pipe pressure.

In the handling of trains equipped with fluid pressure brakes, it sometimes happens, for example, that an angle cock in the train pipe is left closed, or in some other way 20 flow of air through the train pipe is prevented so that upon reducing the train pipe pressure to effect an application of the brakes, no brake will be obtained on cars at the rear of the train pipe obstruction.

According to my invention, it is proposed to provide means adapted to be operated by variations in pressure in an additional pipe line, such as the train signal pipe, for producing a reduction in train pipe pressure, 30 so as to effect an application of the brakes, regardless of any obstruction in the train pipe.

In the accompanying drawing; Figure 1 is a central section of a preferred form of 35 the fluid pressure brake safety device, and Fig. 2 a diagrammatic view of an engine brake equipment, showing the safety device applied thereto.

In its preferred form, the safety device 40 may comprise, as shown in Fig. 1, a casing 1 having a chamber 2 in open communication with the signal line pipe 3. The pressure in chamber 2 acts on one side of a diaphragm 4, the opposite side being subject to the pressure of an adjustable spring 5. A 45 valve 6 controls communication from the chamber 2 to a passage 7 leading to a piston chamber 8 and is adapted to be operated by the diaphragm 4. Within the chamber 8 is 50 a piston or movable abutment 9 for operat-

ing a valve stem 10 carrying a slide valve 11. The valve chamber 12 of the valve 11 is in open communication with the train pipe 13 and valve 11 is provided with a through port 14 adapted in one position of 55 the valve to communicate with an atmospheric exhaust port 15.

A coil spring 16 normally tends to maintain the slide valve 11 in its upper closed position and in order to prevent leakage from 60 the train pipe around the valve stem 10, a seat gasket 17 may be provided on the stem 10 which is adapted to engage a seat 18. A lever 19 connected to valve stem 10 is provided for operating the valve 11 manually. 65

On the locomotive, as shown in Fig. 2, the usual pipe connection 20 is provided containing the reducing valve device 21 and connected to the main reservoir 22, so that the pressure may be normally maintained 70 at a predetermined degree in the signal line pipe 3, and likewise, the usual signal valve device 23 is connected to the signal pipe. In addition to the above, a by-pass pipe 24 is provided having a cock 25 and adapted to 75 connect the main reservoir directly to the signal pipe 3.

In operation, a safety device may be applied to each car, but preferably is only employed on the tail car, the same having 80 connections to the train pipe 13 and signal pipe line 3, as hereinbefore described. The spring 5 is adjusted to a pressure exceeding the normal signal line pressure carried, by a certain amount, say by 10 pounds, for 85 example, so that upon raising the signal line pressure 10 pounds above normal the fluid pressure will overcome the pressure of the spring 5 and the diaphragm will be operated to open the valve 6 and admit fluid 90 under pressure to the piston 9. The piston 9 is thereupon operated to shift the valve 11 and cause port 14 to register with exhaust port 15, so that fluid is vented from the valve chamber 12 and the train pipe 13 95 to effect a reduction in train pipe pressure and the consequent application of the brakes. It will now be evident that when the engineer finds that he cannot operate the brakes in the usual manner by reducing the 100

train pipe pressure it is only necessary for him to operate the cock 25 to admit fluid from the main reservoir to the signal line pipe. This higher than normal pressure in 5 the signal pipe line then operates the safety device at the rear of the train to effect a reduction in train pipe pressure as above described.

With the present device, it is not necessary for the engineer to lose time signaling 10 to the brakeman at the rear of the train to apply brakes as he can make an application directly through the signal pipe.

An equalizing port 26 may be provided 15 through the piston 9, so that upon closing the cock 25 on the engine, the pressure in the signal pipe will fall by leakage through the port 26 until the pressure reduces sufficiently to permit the diaphragm 4 to seat 20 the valve 6. The opposing pressures on the piston 9 then quickly equalize and the spring 16 operates to shift the valve 11 and cut off the further exhaust of fluid from the train pipe.

25 Should leakage occur through the signal line reducing valve 21, the pressure in excess of the degree at which the spring 5 is adjusted will escape past the valve 6 and through the port 20, which is made of such 30 size as to take care of this leakage and thus prevent the movement of the piston 9.

The handle 19 is provided so that the train pipe pressure may be reduced by manual operation of the valve 11 when the 35 brakeman at the rear of the train desires to effect an application of the brakes.

Having now described my invention, what I claim as new and desire to secure by Letters Patent, is:—

40 1. The combination with a fluid pressure brake operating upon a reduction in train pipe pressure for effecting an application of the brakes, of an additional pipe line and a valve device operated by varying the 45 pressure thereon for effecting a reduction in train pipe pressure and a valve mechanism subject to the pressure in said additional pipe line for controlling the operation of said valve device.

50 2. The combination with a fluid pressure brake operating upon a reduction in train pipe pressure for effecting an application of the brakes, of a signal pipe line and means operated upon an increase in signal 55 line pressure for effecting a reduction in train pipe pressure.

3. The combination with a fluid pressure brake operating upon a reduction in train pipe pressure for effecting an application 60 of the brakes, of a signal pipe line and means operated upon increasing the pressure in the signal pipe line above normal for effecting a reduction in train pipe pressure.

4. In a fluid pressure brake, the combina-

tion with a train pipe, of an additional pipe 65 line, a valve for controlling a train pipe vent port, a movable abutment operated by fluid pressure for actuating said valve, and valve means operating upon an increase in signal line pressure for supplying fluid to 70 said abutment.

5. In a fluid pressure brake, the combination with a train pipe, of a signal line pipe, a valve for controlling a vent port from the train pipe, a movable abutment 75 having means for equalizing the pressures on opposite sides and operated by fluid pressure for actuating said valve, and valve means operating upon an increase in signal line pressure for supplying fluid to 80 said abutment.

6. In a fluid pressure brake, the combination with a train pipe, of an additional pipe line, a valve mechanism governed by the pressure in the additional pipe line for controlling a train pipe vent port, and manually operated means for also actuating 85 said valve mechanism.

7. In an air brake mechanism comprising 90 separate brake and signal pipes, the combination with the brake and signal pipes, of a discharge valve in communication with the brake pipe for setting the brakes, means actuated by increasing the signal pipe pressure above normal to operate the discharge 95 valve, whereby an effective pressure may be maintained at all times for signaling purposes, and means under the control of the engineer for varying the air pressure in the signal line.

8. In an air brake mechanism comprising 100 separate brake and signal pipes, the combination with the brake and signal pipes, of a conductor's emergency valve for applying the brakes, a tripping device coöperating 105 with said emergency valve for operating the same and actuated by increasing the air pressure in the signal line above normal, and means under the control of the engineer for varying the air pressure in the signal 110 line.

9. In an air brake mechanism comprising 115 separate brake and signal pipes, the combination with the brake and signal pipes, of a discharge valve in communication with the 120 brake pipe for setting the brakes, means operable to trip said discharge valve and actuated by increasing the signal line pressure above normal, means opposing the operation of said tripping means when the signal 125 line pressure is at normal or less, and means controllable from the engine for varying the air pressure in the signal line.

10. In an air brake mechanism comprising 125 separate brake and signal pipes, the combination with the brake and signal pipes, of an emergency valve for applying the brakes, a tripping device coöperating with the

emergency valve for operating the latter and actuated by increasing the air pressure in the signal line above normal, means for returning the tripping device to its normal position, and means controllable from the engine for varying the air pressure in the signal line.

In testimony whereof I have hereunto set my hand.
